UNITED STATES PATENT OFFICE.

LEROY COOK, OF WORCESTER, MASSACHUSETTS.

RAIL-BOND.

SPECIFICATION forming part of Letters Patent No. 561,698, dated June 9, 1896.

Application filed April 11, 1896. Serial No. 587,217. (No model.)

To all whom it may concern:

Be it known that I, LEROY COOK, a citizen of the United States, residing at Worcester, in the county of Worcester and State of Massachusetts, have invented a new and useful Improvement in Rail-Bonds, of which the following is a specification, accompanied by drawings forming a part of the same, in which—

10 Figure 1 is a top view of a portion of rails united by my improved bond, a part of said rail being represented in horizontal sectional view on the plane of the bonds. Fig. 2 represents a portion of the waist of a rail with 15 one of my improved rail-bonds inserted, said bond being shown in central horizontal sectional view. Fig. 3 is an end view of one of my improved rail-bonds previous to its insertion in a rail, showing the end of the conducting-wire in position. Fig. 4 is a central sectional view of the inner copper sleeve. Fig. 5 is a central sectional view of the outer steel sleeve, and Fig. 6 a portion of a rail in sectional view with one of my improved rail-bonds placed in proper position to be driven 25 into the rail.

Similar letters refer to similar parts in the several views.

Referring to the drawings, A A denote portions of two rails united by rail-bonds embodying my invention.

B denotes the electrical conducting-wire electrically connected at its ends with each of the rails A A by means of the rail-bonds C C.

35 The rail-bonds C C are duplicates of each other, and consist of an inner sleeve D, inclosing the end B' of the wire B, and an outer sleeve E, inclosing the inner sleeve D. The inner sleeve D is preferably of copper or some 40 soft and ductile metal which is a good conductor of electricity and is cylindrical on its outer surface with a concentric hole D' to receive the end of the wire B, and is provided on one side with a slot D² communicating 45 with the central opening D'. The outer sleeve E is preferably of steel or some relatively hard non-compressible metal, and is slotted on one side, as at E'. The sleeve E fits the outer cylindrical surface of the inner 50 sleeve D, and its outer surface E is cylindrical, except at one end, where it is slightly beveled for a short distance, as at E³. The

outer diameter of the steel sleeve E is somewhat larger than the diameter of a hole A² in the rail A. The end B' of the wire B is inserted in the hole D' in the soft-metal sleeve D. The soft-metal sleeve is then inserted in the hard-metal sleeve and both are presented to a hole A² in the rail with the tapered end E³ of the outer sleeve inserted in the hole A². 55 Both sleeves are then driven into the rail with a sledge-hammer, into the position represented in Figs. 1 and 2, with the central section of the bond held in the waist of the rail A and with the end of the bond projecting slightly 60 from both sides of the rail. As the bond is driven into the rail the sleeve E is contracted in diameter, thereby compressing the soft-metal sleeve D and closing the slots D' and E', said slots being preferably placed on 65 diametrically opposite sides of the band. As the tapered end E³ of the bond emerges from the hole A² the force of the blow struck upon the opposite end, together with the friction between the side of the hole and the outer 70 surface of the sleeve E, will cause the end E³ to expand, bringing the sleeve straight on its outer surface, as at E⁴, and the bevel to be transferred to its inner surface, as at E⁵, and the inner end of the soft-metal sleeve D will 75 also be expanded over the inner beveled surface E⁵, making the diameter of the soft-metal sleeve greater at its inner end F than in its cross-section inclosed in the rail, as at G. The force of the blow also slightly upsets the 80 driven end H, so the bond will be held from movement within the rail in either direction and preventing the bond from being jarred 85 out of the rail.

The outer sleeve E prevents the abrasion 90 of the outer surface of the soft-metal inner sleeve, and also allows the inner sleeve to be brazed to the end of the wire or to the end of a twisted cable of soft-copper wires. In such cases the sleeve D, attached to the end of the 95 cable, is passed through the hole A². The outer sleeve E is then applied, and both are driven into the rail.

What I claim as my invention, and desire to secure by Letters Patent, is—

1. As an article of manufacture, a rail-bond consisting of an inner soft-metal split sleeve, having a central hole to receive the wire and an outer split hard-metal sleeve having a cy-

lindrical outer surface with a tapered or beveled end, substantially as described. 2. The combination with an electrical conducting-wire, of a sleeve inclosing the end of said wire, said sleeve being cut apart on one side and consisting of a soft and ductile metal and an outer split sleeve inclosing said soft-metal sleeve and having one end tapered or beveled, substantially as described. 3. The combination with a railway - rail, provided with a hole to receive a wire, of an electrical conducting-wire, a soft-metal sleeve inclosing the end of said wire and cut apart at one side, and a hard-metal split sleeve inclosing said soft-metal sleeve and held within the hole in said rail, said outer sleeve being

normally larger in diameter than the diameter of said hole, substantially as described.

4. In a rail-bond, the combination of an inner sleeve adapted to inclose the end of an electrical conducting-wire, and consisting of a soft non-elastic but compressible metal, such as copper, and an outer sleeve inclosing said soft-metal sleeve, said outer sleeve consisting of a hard elastic and relatively non-compressible metal such as steel, substantially as described.

Dated this 7th day of April, 1896.
